(57) CLAIM

We claim the ornamental design for the indented football, as shown and described.

DESCRIPTION

FIG. 1 is a perspective view of the football showing our design;

FIG. 2 is a top plan view thereof;

FIG. 3 is a right side view thereof, the left side being a mirror image;

FIG. 4 is a bottom plan view thereof; and,

FIG. 5 is a front end view thereof, the rear end view being a mirror image.

1 Claim, 2 Drawing Sheets

FIG. 1

FIG. 4FIG. 5
